UNITED STATES PATENT OFFICE.

ADOLPH G. KAUFMAN, OF NEW YORK, N. Y.

RANGE JET BURNER.

Application filed November 13, 1923. Serial No. 674,477.

This invention concerns heating apparatus in which liquid fuel is used, and in particular, types adapted for domestic purposes.

The invention has as one of its objects to produce an apparatus portable or semi-portable in its nature and so simple in its construction and operation that no difficulty is encountered in its use.

Another purpose is to provide a device in which a single burner, two burners or multiples thereof may be combined and used as required, these burners or heating units being entirely open to atmospheric air and subjected to draft from under the burner casing.

A further aim is in the provision of a type of burner in which the fuel is effectively pre-heated, directed in gaseous form against a circular corrugated deflecting plate, and there consumed in such manner as to distribute the flame and heat in an advantageous manner.

Other objects are, to provide an initial igniting device adapted for cleanliness, economy and safety, and particularly for inducing an air draft whereby atmospheric air is mixed with the flame and delivered in such manner as to rapidly raise the gas generating or expansion chamber and burner to such temperature as may be required to convert oil entering therein into a gaseous condition.

Still another object is the provision of a plurality of deflecting plates on a single friction collar so that when one deflecting plate is presented to the flame, the other or others will be away from the flame to be readily cleaned of soot or other accumulations of carbon.

The several objects are secured by the novel arrangement of specifically formed parts, as later described and illustrated in the appended drawing, in which:—

Figure 1 is a fragmentary plan view of a multiple burner apparatus made in conformity with the invention, parts being in horizontal section on the line $\alpha-\alpha$ of Fig. 3.

Figure 2 is a partial transverse sectional view taken on plane corresponding to line 2—2 of Fig. 1, but showing a slight modification.

Figure 3 is another sectional view taken in a plane at a right angle to Fig. 2 on line 3—3 of Fig. 1 but showing a modification of the deflector plate arrangement.

Figure 4 is a side view of a further modification of the deflector plate arrangement.

Figure 5 is a top view and Figure 6, a side view of another form of deflector plate unit.

Figures 7, 8 and 9 are side views of still other forms of deflector units.

In Figure 1 appears one end of a generally flat topped support frame arranged to receive one or more pairs of burners one of which, at the left, being a plan and the other on the right, being a section as indicated by the line $\alpha-\alpha$ of Figure 3.

The support frame, preferably a metal casting, is generally rectangular, although its contour may be fancifully made in any preferred shape, its upper surface 10 being essentially level having openings 11 to lighten its weight and permit of free air circulation.

The outwardly beveled marginal walls 12 terminate in beaded edges 13 suited to rest upon any convenient level surface and contain openings 14 corresponding in purpose with the openings 11.

Below each burner an oblong rectangular depression is formed in the frame, its walls 15 flaring slightly inward to the flat, level bottom 16, from which rise vertical walls 17 joined by a cap 18 raised to approximately two thirds of the distance from the bottom 16 to the frame top 10.

Said cap 18 and also in the modified form, the sidewall 17, contain perforations 19 allowing air from below the frame to enter the channelled recess 20, interjacent the walls 15 and 17, this recess having disposed in it a quantity of non-inflammable fiber, as asbestos, to act as a wick 21, the channel constituting a fire box as will later be seen, and centrally on the cap 18 is a rib 22 raised above the surface of the frame 10, as best seen in Figures 2 and 3.

Formed with the side walls 15 are raised and outwardly curved wings or guards 23, highest at their centers and adapted to direct liquids into the recesses; and extending between adjacent recesses are grooves 24 for collecting excess liquid on the surface of the frame, directing the same into the recesses.

An independent liquid fuel supply pipe 25 leads to a raised boss 26 formed on the frame continuous to one end of each recess and is held therein by the lock nut 25' and fixed in the boss is a tube 27, bent at a right angle to extend over the perforate plate 18 at a spaced distance above it, and then turned re-entrantly, forming a bend 28, its end 29 having fixed to it a burner head 30 directly over

the center of the rib 22, and having a jet nozzle 31 removably engaged containing one or more perforations directed upwardly, there being a plug 32 removably engaged in the end of the burner head for cleaning purposes.

A plurality of circular sheet metal discs 33, having radial corrugations, are attached by friction band 34 to the horizontal member of the tube 27, one of said discs being disposed directly over the nozzle 31 so that streams leading outward impinge on the disc and by it are directed outwardly around its entire circumference.

If it be necessary to clean any accumulation of sooty deposit from the disc this may be easily and conveniently done by rotating the band 34 so as to present a clean disc to the flame, likewise rendering the sooty disc accessible for cleaning.

I have also found it desirable to make these deflector discs into a removable and readily attachable spreader unit some embodiments of which are shown in Figures 5 to 9. In Figures 5 and 6, I have illustrated a spreader stamped of a single piece of material and formed to provide parallel deflector discs 33 joined by the relatively narrow strip 40, the opposite side of the discs 33 being provided with tongues 41 pierced to provide a catch 41^a for retaining the arms 42 of the spreader unit in engagement with the tube 27; the arms 42 being also integral with their respective discs and bent at right angles to them to engage tube 27. The embodiment shown in Figure 7 is in all general respects similar to Figures 5 and 6 except that three instead of two discs are provided from a single stamping. Obviously, if the catch 41^a be opened the discs may be spread apart and thus removed from the tube 27. It is of great importance that these spreader units be made of a single piece of material in order to avoid the use of rivets which are always a source of much annoyance because of the readiness with which they collect soot and hold such accumulations against all efforts to cleanse thus lowering the efficiency of the spreader discs.

While the preferred form of my spreader unit is stamped of a single sheet of material, still I have shown two embodiments of removable spreader units in Figures 8 and 9 wherein the deflector discs 33 are riveted or otherwise fastened as at 43 to spring clamps 44 for easy attachment or removal from the tube 27.

I have shown the spreader discs in Figures 5, 6, 7, 8 and 9 as having flat surfaces but obviously they may be made with radial corrugations if desired, as shown in Figures 1, 2, 3 and 4.

For some purposes it may be desirable to concentrate the heat from the channel 20 in which case a perforate shield, as indicated

at 37 in Figure 2, may be used, the same resting upon ledges 15' on the inner surface of the walls 15, the walls of said shield converging towards the open top as shown.

In operation oil being entered in the tube 27, which is of relatively large area, will eventually flow out of the nozzle 31 and saturate the wick 21.

Upon lighting the wick, heat will arise, affecting the oil in the tube 27, generating gas so that for a brief time both gas and oil will issue, hence the use of the guards 23, which will direct oil spray to the wick recess.

The flames from the wick and air entering the perforations 19 are intensely hot and following the walls 17, over the cap, and along the raised rib 22 are concentrated to impinge upon the head 30 which action soon causes a pure gas to issue so that the same upon being ignited, strikes the disc 33 and is directed outwardly thereby, enough heat however being transmitted to the tube 27 to continue the process of gas making, draft being supplied from under the burner through the perforations 19 and openings 11 and 12.

In the initial operation, should an excess of oil enter the recess 20, it will be taken care of by the overflow pipe 35 set in a boss 36, formed on the bottom 16, and be delivered outwardly of the apparatus.

From the foregoing it will be apparent that one or more of the burners may be used as required; that the operation is exceedingly simple, and that provision has been made for the economical production of heat in an effective manner.

It is to be understood however, that the foregoing disclosure is largely descriptive, rather than limitative, and that minor modifications can be made as experience dictates within the scope of the attached claims.

Having thus set forth the invention, including the manner of its operation and use, what I claim as new and desire to secure by Letters Patent is:—

1. A liquid fuel heating apparatus comprising a frame having oblong depressions in its upper surface, raised elements in the depressions forming channels therebetween, wicks in the channels, raised ribs centrally on said elements, a return bend generator tube fixed in said frame to extend in a vertical plane centrally over each depression, a burner head on the end of each said tube, a jet nozzle fixed in each said head to extend upwardly, means for supplying fuel to each said tube, and means for diverting heat from said burner head radially outward.

2. A liquid fuel heating apparatus comprising a frame having an oblong depression in its upper surface, a raised perforate element in the depression forming channels therebetween, wicks in the channels, a raised rib centrally on said element, a return bend

generator tube fixed in said frame, the bend in said tube being in a vertical plane, a head on the end of said tube disposed directly over the center of the depression, a removable plug in the end of said head, means for supplying fuel to said tube, means for withdrawing an excess of fuel from the wick channels, and means for collecting oil on top of said frame and returning it to the depressions.

3. A liquid fuel heating apparatus comprising a frame having an oblong depression in its upper surface, a raised perforate element in the depression forming channels between it and the walls of the depression, wicks in the channels, a raised rib centrally on said element, a return bend generator tube fixed in said frame, the bend in said tube being in a vertical plane, a head on the end of said tube disposed directly over the center of the depression, a removable plug in the end of said head, means for supplying fuel to said tube, means for withdrawing an excess of fuel from the wick channels and a perforate guard adapted to rest in the depression, the walls of said guard being

convergingly inclined to its open top below said generator tube.

4. A liquid fuel heating apparatus comprising a raised hollow frame having openings in its top and side walls and containing oblong rectangular depressions in the top, a hollow element centrally disposed in each depression, said element extending upward to lesser height than the top of said frame and containing perforations in its walls, wings on the side walls of the depressions, a wick in the channel surrounding said hollow central element, a rib on said element extending above the frame top, a return bend generator tube fixed on said frame, said bend being in a vertical plane and said tube extending over said hollow element, a burner head on said tube disposed directly over the center of said element, means for deflecting vapor issuing from said burner head outwardly from above said head, and means for supplying oil to said tube.

Signed at New York in the county of New York and State of New York this 5th day of November, A. D. 1923.

ADOLPH G. KAUFMAN.
